UNITED STATES PATENT OFFICE.

LOUIS E. PECK, OF GREENFIELD, MASSACHUSETTS, ASSIGNOR TO THE THREADWELL TOOL COMPANY, OF GREENFIELD, MASSACHUSETTS, A CORPORATION OF MASSACHUSETTS.

HACK-SAW FRAME.

Application filed February 19, 1925. Serial No. 10,377.

To all whom it may concern:

Be it known that I, LOUIS E. PECK, a citizen of the United States, residing at Greenfield, in the county of Franklin and State of 5 Massachusetts, have invented a new and useful Hack-Saw Frame, of which the following is a specification.

The principal objects of this invention are to provide a hack saw frame of comparatively simple construction and of such form that the number of parts of the frame is reduced to a minimum; to construct the frame so that the greater strength is where it is needed at a point near the handle, thus increasing 10 the rigidity of the frame and reducing the tendency to bend, and also to reduce the cost of manufacture.

Other objects and advantages of the invention will appear hereinafter.

Reference is to be had to the accompanying drawings, in which—

Fig. 1 is a side view of a hack saw with a frame constructed in accordance with this invention and shown partly in longitudinal section;

Fig. 2 is a plan of the handle end of the frame;

Fig. 3 is a rear end view of the upper part of the handle;

Fig. 4 is a side view of one end of the telescoping element of the frame;

Fig. 5 is a view of the upper part of the locking or latch member;

Fig. 6 is a plan thereof;

Fig. 7 is a view of the adjustable saw blade connection; and

Fig. 8 is a transverse section thereof on the line 8—8 of Fig. 1.

I have shown the invention as applied to a construction having a wooden handle 10 which is slit down at the top to provide a longitudinal slit 11 all along the top and which is extended down at the two sides to form extensions 13 separated from each other by a central tongue 14 of wood integral with the handle. Into this slit I insert the rear end of a doubled over sheet metal bar 12 and secure it by rivets 15. These rivets are located in the slot extensions 13 and they also pass through the tongue 14. Thus the doubled over bar is firmly secured between the wooden surfaces on both sides when the rivets are secured in position. This doubled over bar extends forward only 55 a short distance and constitutes a very strong

and rigid part of the frame located at the handle end and extending forward from it only a little way.

The telescoping is secured by providing a bar 17 which is of such size and shape as to slip into the U-shaped bar 12 at the top thereof and be received between its upper surface and the top of the tongue 14. These parts constitute the guide for the telescoping bar which has notches 19 in the lower edge. The saw blade is supported at its extreme end by a support 18 which is of well known construction and need not be described in detail.

The end of the saw blade nearest the handle is supported by a locking or latch member 20. This is pivoted on a stud or rivet 21 supported at both ends by the U-shaped bar 12 near the lower edge thereof and at a short distance in front of the handle. The latch member has a projecting arm 22 having a rounded projection 23 at its extreme end which extends forwardly from the handle. This projection engages in the notches 19 to lock the sliding bar 17 in any adjusted position.

This latch member 20 extends downwardly and is provided with a fastening loop 24 having a square passage therethrough in which is received a square slide 25 having a pin 26 for holding the saw blade. The slide has a screw thread inside extending longitudinally, into which extends a screw 27 having a knurled head 28 thereon. This screw adjusts the slide as may be desired and it is a substantial improvement over the ordinary screw adjustments on the market because the screw thread is entirely concealed within the slide. Therefore it is not exposed to the weather and is not likely to rust. Furthermore, the ordinary screws used in this place are square and have screw threads merely on their four corners which are not of full strength. This one gives considerable additional strength. When the saw is not in place this slide is free to move in its slot, being held against dislodgment from one end by the neck of the head 28. It also provides a smooth head against which the knuckles of the user are not likely to be injured in the operation of the saw.

The operation of the device will be obvious. In order to change the length of the handle the piece 20 is swung on its pivot, as indicated in dotted lines in Fig. 1 to unlock it and then any desired adjustment can

be made when the saw blade is not in place. The swinging of the member 20 to the full line position and the tightening up of the saw blade effectually, locks the parts so that 5 they cannot get loose in operation. It is a very strong and simple construction and considerable saving of metal and metal working operations is accomplished by its use.

10 Although I have illustrated and described only a single form of the invention, I am aware of the fact that modifications can be made therein by any person skilled in the art without departing from the scope of the 15 invention as expressed in the claims. Therefore I do not wish to be limited to the details herein shown and described but

What I do claim is:—

1. In a hack-saw frame, the combination 20 with a handle a U-shaped bar fixed directly in the handle and projecting therefrom and having a pivot pin near its extreme end, and a single bar constituting the end of the frame telescoping in the U-shaped bar and 25 adapted to be adjusted along the same and provided with a series of notches along its lower edge, of a locking member pivoted on said pivot pin and having a projection adapted to enter one of said notches so that 30 the bars cannot be moved longitudinally with respect to each other and provided with means for holding one end of the saw blade.

2. As an article of manufacture, a two piece hack-saw frame consisting of a pair 35 of bars, one of them telescoping into the other, a handle in which one bar is firmly secured, the other bar constituting the extreme end of the frame and having means for supporting one end of a saw blade, and 40 an end piece pivoted to the U-shaped bar and having means for preventing the sliding of the bars relatively to each other and means for supporting the other end of the saw blade.

45 3. In a hack-saw frame, the combination of a bar constituting a part of the frame,

a handle rigidly fixed thereto, an end member having a horizontal top part sliding along the bar and having notches along its lower edge, and a locking member pivoted 50 to, and projecting down from, the bottom of the bar and having a projection adapted to enter said notches to provide adjustment and having means at the bottom for attaching 55 a saw blade.

4. In a hack-saw frame, the combination of a bar constituting a part of the frame, an end piece at the handle end having a horizontal top part located along the bar and pivoted to it and projecting down from 60 the bottom of the bar and having an opening at the bottom, and a slide having a pin for holding the end of the saw blade located in said opening.

5. In a hack-saw frame, the combination 65 of a bar constituting a part of the frame, an end piece having a horizontal top part located along the bar and pivoted to it and projecting down from the bottom of the bar and having an opening at the bottom, a 70 slide having a pin for holding the end of the saw blade and located in said opening, and a screw screwing into the slide longitudinally for adjusting it and concealed in said slide and said opening.

6. In a hack-saw frame, the combination with a handle having a groove in the top, of a U-shaped bar constituting a part of the frame located and fitting in said groove, an end piece having a horizontal top part 80 located in the interior of the U-shaped bar and pivoted to it and projecting down from the bottom of the U-shaped bar and having a square opening at the bottom a slide having a pin for holding the end of the saw 85 blade and located in said opening, and a screw having a round head screwing into the slide longitudinally for adjusting it.

In testimony whereof I have hereunto affixed my signature.

LOUIS E. PECK.
